United States Patent Office.

M. A. MYER, OF DECATUR, ILLINOIS.

Letters Patent No. 61,755, dated February 5, 1867.

IMPROVED BOOT AND SHOE-BLACKING MACHINE.

The Schedule referred to in these Letters Patent and making part of the same.

TO ALL WHOM IT MAY CONCERN:

Be it known that I, M. A. MYER, of Decatur, in the county of Macon, and State of Illinois, have invented certain new and useful improvements in Machines for Blacking Boots and Shoes; and I do hereby declare the following to be a full, clear, and exact description of the same, reference being had to the accompanying drawings, making a part of this specification, in which—

Figure 1 represents a front elevation of the machine; and

Figure 2 represents a side elevation thereof.

Similar letters of reference, where they occur in the separate figures, denote like parts of the machine in both of the drawings.

My invention consists in the combined action and operation of a blacking and polishing brush driven by machinery, and so that whilst in motion, the blacking brush may be extended down to the blacking box for its supply, as will be explained.

To enable others skilled in the art to make and use my invention, I will proceed to describe the same with reference to the drawings.

On a base or support, A, is placed the frame B, for holding the several parts of the apparatus. C is a shaft, revolved by a crank, D, or otherwise, and has upon it a gear-wheel, E, that meshes with and turns a pinion, F, that is supported upon a stud or bearing in the frame B. There is connected to the pinion F a crank-wheel, a, to which one end of a pitman, G, is connected, the other end of said pitman being attached to an arm or lever, H, fastened on a shaft, b, also supported in the main frame. In two projecting lugs, c e, attached to the main frame, there is supported a rod, d, which is jointed at e, and has a button or knob, f, at its upper end, and a blacking brush, g, at its lower end, and is, moreover, guided by the rods i j, the former passing through a support, k, attached to the main frame, and the latter, j, passing through a slot in the end of the vibrating lever H. The rod d is held up in the position shown in the drawings by means of a spring, l, but may at any time, and whilst in motion, be pressed down until its brush, g, will come in contact with the blacking, the box containing which may be placed in the recess m, and held in place by the button n, and on being released its spring, l, will raise it up again. The arm or arms H on the shaft b receive their vibratory motion from the crank-wheel a and impart it to the shaft b and to the polishing brush I, connected to it by a rod, o. Underneath this polishing brush there is a yielding stool or foot-support, p, by which a boot or shoe may be turned or properly supported and presented to the polishing brush after it has received the blacking from the other brush, g. The brush g has also a reciprocating motion given to it by means of its guiding rod, j, passing through one of the levers or arms H which lever or arm, as before stated, receives its motion from the crank-wheel a.

The operation of the machine is simple: The blacking being placed at m, and the machine set in motion, the brush g is forced down into it by pressing on the knob f, and when supplied it is released and is raised up by the reactionary spring l. The boot or shoe is then placed within the influence of the brush g, and receives a coating of blacking from it. It is then placed on the support p, where it is presented to the polishing brush and speedily polished.

Having thus fully described my invention, what I claim therein as new, and desire to secure by Letters Patent, is—

In combination a polishing brush having a reciprocating motion, a blacking brush also having a reciprocating motion, and capable also, whilst in motion, of being thrust down for a supply of blacking, and rising again whilst it continues to vibrate or reciprocate, substantially as herein described and represented.

M. A. MYER.
